ABRADING TOOL

Thomas F. Quigley, Cleveland, Ohio, assignor, by
mesne assignments, to Micromatic Hone Corporation, a corporation of Michigan

Application November 3, 1927, Serial No. 230,799

3 Claims. (Cl. 51—184.3)

This invention relates to honing or abrading devices or tools particularly adapted to and intended for the honing or finishing of cylinders, and one of the objects of the invention is to provide an improved device in which the shoes or abrading members are adjustable radially to fit cylinders of different diameters, and longitudinally to grind a hole that is exactly cylindrical and of equal diameter throughout its length.

10 A further object of the invention is to provide improved means for rotating the tool and to start or stop relative rotation between the parts.

A further object of the invention is to provide improved means for adjusting the abrading members, by the operation of a pair of adjusting cones contained in a hollow mandrel which carries said members.

The driving devices include a planetary gearing the driving member of which is operated by a shank to which the power is applied and the driven member of which is connected to the mandrel. Associated with this is a clamping device which can be operated to start or stop the transmission.

The device includes universal joints between the mandrel and the driving device and between the screw which operates the cones and the driving devices, so that the latter can take a position out of alignment with the active parts of the tool.

30 A further object of this invention is to provide an improved method of taking care of the unequal wear of the abrading surfaces of the shoes, by permitting a slight rocking action of the fluted adjusting cones, thereby leveling said abrading surface and grinding a hole that is exactly cylindrical and of equal diameter throughout its length.

With these and other objects in view one form of the device is hereinafter described and is illustrated in the accompanying drawings in which Fig. 1 is a longitudinal section through the tool; Fig. 2 is a cross section on line 2—2 of Fig. 1; Fig. 3 is a cross section on line 3—3 of Fig. 1; Fig. 4 is a cross section on line 4—4 of Fig. 3, and Fig. 5 is an enlarged partial section taken on line 5—5 of Fig. 1; Fig. 6 is a cross section taken on line 6—6 of Fig. 1; Fig. 7 is a cross section taken on line 7—7 of Fig. 1; Fig. 8 is a cross section taken on line 8—8 of Fig. 1 and Fig. 9 is a cross section on line 9—9 of Fig. 1. Fig. 10 is an inner end view of the tool. Fig. 11 is an elevation of the lower end of the driving spindle shown in section in Fig. 1; Figs. 12 and 13 are external views of the expanding member shown in Fig. 1 and shows the same contracted and extended respec-

tively. Fig. 14 is a side elevation of one of the shoes.

Referring specifically to the drawings, 1 is the abrasive material fastened to shoe 2 which is held in place in slots in the mandrel 3 by the end plates 4 and the screws 5. The shoes 2 have pins 6 fastened to them and passing through holes in mandrel 3 to contact with the cones or fluted tapered pieces 7 and 8. Part 8 fits and telescopes into part 7 and the two pieces are held together by the screws 9. Springs 10 are fastened to shoes 2 by screw 11 and to the mandrel 3 by screw 12. Mandrel 3 has ears 13 into which are screwed pins 14 which fit into holes in the ring 15. Similar pins in similar lugs 16 of the extension tube 17 fit at right angles to the pins 14 into similar holes in ring 15, thus forming a universal joint. The rod 18 has right and left handed threads formed on it and is fastened to block 19 by pin 20 as best seen in Figure 1. The slotted collar 21 fastened to mandrel 3 by screws 22 and retained in the groove formed on block 19 prevents any end-wise motion of said block 19 which has a lug 23 on which sleeve 24 is loosely pivoted by means of pin 25. Sleeve 24 is bored out slightly greater than the diameter of lug 23 to allow for a slight motion and is fastened to rod 26 by pin 27. Rod 26 is square in section.

Extension tube 17 has pins 17a screwed into the upper end of it engaging with bayonet slots 28 in the lower part of shank 29 which permits easy disconnection and removal of the hone. The shank 29 has a taper on the upper end of it to fit a tapered socket on the machine, and is recessed on the other end to take the drive pinion 30, bushings 31 and 31a and retaining collar 33 which is fastened by screws 32 to shank 29. Pinion 30 meshes with an idler pinion 34 which in turn meshes with the internal gear 35. Idler pinion 34 rotates freely on pin 36 and the internal gear 35 is fastened to the sleeve 37 by screws 38. The outer sleeve 37 has a bronze bushing 38a pressed into it and is free to rotate on shank 29 and is prevented from endwise motion by the internal gear 35 fastened to one end of it and the nut 39 which is screwed onto and against a shoulder on shank 29. A groove near the upper end of sleeve 37 carries the clamping arms 40 and 40a which are capable of being drawn together by means of the taper seated lever 41 which rotates around the screw 42 fastened to arm 40a by nuts 43 and 43a. This lever also carries pin 44 which engages pin 45 in arm 40 and prevents the lever from moving too far back-

wards. Arm 40a has a bar 46 fastened to it by screw 47 which same engages a lug on the machine and prevents rotation.

A micrometer adjustment consisting of the 5 sleeve 48, positive stop block 49 and ratchet 50 is mounted on the shank 29 just below the taper. The ratchet is secured to shank 29 by taper pin 51 and has a screw thread formed on its outer surface to take the nut 52 which is secured in 10 place by screw 53.

The pawl 54 is fastened to the positive stop block 49 by the screw 55 around which it pivots and is kept in engagement with ratchet 50 by spring 56 which fits over a small pin 57 on pawl 15 54 and into a hole in the side of slot 58 milled on the side of stop block 49 to receive the pawl 54.

The positive stop block 49 also carries the pin 59 which projects far enough from its under surface to engage a similar pin 60 screwed into and 20 projecting from sleeve 37. The sleeve 48 is capable of being turned thru 360° or one complete turn and carries the screw 61 which projects into the recess 58 and engages pawl 54.

The action of the tool is as follows: The tool 25 as shown in Fig. 1 rotates as a unit, there being no relative motion between the parts as long as arms 40 and 40a are not clamped tight against sleeve 37.

After the hone is inserted into an engine cylinder it must be expanded a sufficient amount to 30 abrade the inner surface of said cylinder. This result is obtained by turning sleeve 48, thereby depressing pawl 54 by means of screw 61 and releasing same from the ratchet 50, and stop 35 block 49 can then be rotated as a unit with the sleeve 48 carrying pin 59 backward or away from pin 60 according to the adjustment desired. As soon as the sleeve stops moving pawl 54 is again forced into engagement with ratchet 50 thereby 40 locking stop block 49 to ratchet 50. If we now clamp sleeve 37 between the arms 40 and 40a, holding it stationary, and revolve shank 29, the ratchet 50 will revolve with it, carrying the block 49 and pin 59 as a unit. These parts can 45 only rotate till pin 59 strikes against pin 60, the arc of rotation being determined by the amount pin 59 and 60 are separated by movement of sleeve 48, and this determines the amount the hone is 50 expanded as hereinafter described. When pin 59 strikes pin 60 the operator releases sleeve 37 and the tool again rotates as a unit.

When sleeve 37 is held stationary the continued motion of part 29 causes idler pinion 34 to rotate 55 on the internal gear 35, driving pinion 30, rod 26, block 19 and screw 18 in or out depending on the rotation. The shoes are thus either expanded or contracted by means of the pins 6 contacting with the parts 7 and 8 which are fluted right hand and left hand to permit the shoes to rock slightly. 60 It will be noticed that when the shell 37 is held by the clamp 40 and 40a the driving pinion 30 is rotated, turning the squared rod 26 to expand or adjust the cones away from each other until the shoes press against the surface of the 65 cylinder, after which the motion picks up the tool and rotates the same in the cylinder, the drive then being through the shank 29, and pins 17 and 17a to the extension tube 17 and the head of the tool. The universal joints permit lateral 70 variation of the axis, the squared rod 26 having a sliding fit in the pinion 30 to permit this.

An important feature of this invention resides 75 in the tapered parts 7 and 8 which telescope with each other and are guided by the head of the screw 9 so that they can slide in and out without

turning with respect to each other. The tapered ends are fluted and it will be noted that surfaces "A" and "B" slant in opposite directions. Now if the abrading material wears faster on one end than on the other the pressure of pins 6 on surfaces "A" and "B" will vary and due to their opposite slants, this pressure will cause the expanding members to rotate or rock slightly, equalizing the pressure and causing the abrading material to grind a hole that is the same diameter throughout its length. To permit this action, the ends 2a of the shoes 2 are machined to a true radius from the middle of their center line, as shown in Fig. 14, allowing enough clearance so that the shoes can move in or out and also rock 15 in or out at respective ends without any end movement so that they cannot change position endwise when the tool comes to a sudden stop or reverse. This does not allow the shoes to crawl or move endwise on the tapered members, 20 but holds the set positive, and by reason of the contact of the flutes against the beveled sides of the pins one shoe cannot deflect from the wall being ground but all the shoes have to move or are held out together. The rocking motion referred to is permitted by the slight turning of the cones, which is permitted by the lost motion in the train of gearing 30, 34 and 35. The inner ends of the pins 6 have a slight clearance in the 25 flutes, to permit the slight turning movement of the cones, and by such movement, when one set of pins moves in slightly the other moves out 30 slightly, and so tilts the shoes.

The cones may be contracted by rotating sleeve 37 backward by hand to the extent permitted by 35 the pin 60, that is, until it strikes the pin 59, the shank 29 standing still and the reverse drive being from the internal gear 35 thru idler 34 to pinion 30 and thence to the cones by means of 40 rod 26, the right and left screws.

It will readily be seen that the arrangement 45 of parts affords an efficient and ready means of adjusting the amount of the cut and expanding the cutting members to a size to guarantee this amount.

The device is capable of extensive modifications 50 within the scope of the following claims.

I claim:

1. In an abrading tool, the combination of a 55 hollow mandrel, a set of abrading members adjustable radially therein, pins connected to said members and extending into the mandrel, and cones in the mandrel engaging the inner ends of the pins, the cones being fluted where they engage the pins, thereby permitting self-adjustment for equalizing the pressures on the ends of the abrading members.

2. In an abrading tool, the combination of a 60 hollow mandrel, a set of radially adjustable abrading members carried thereby, a pair of cones adjustable in the mandrel and operatively connected to the said members to adjust the same, said cones having telescopic mounting upon each other, and means to adjust the cones toward or from each other.

3. The combination stated in claim 2, said 65 means including an oppositely threaded screw on which the cones are mounted.

4. The combination stated in claim 2, the telescopic mounting including means to prevent relative rotation of the cones with respect to each other.

5. In an abrading tool having an abrading 70 head, the combination of an abrading element radially adjustable in said head, an adjusting 75

- cone axially and rotatively movable in said head and having a surface for engaging said element, means for effecting axial movement of said cone in said head to adjust said element, said surface being so formed that rotative movement of said cone provides a further adjustment of said element.
6. In an abrading tool having an abrading head, the combination of an abrading element 10 radially adjustable in said head, an adjusting cone axially and rotatively movable in said head and having a surface for engaging said element, means for effecting axial movement of said cone in said head, to adjust said element, said cone being engaged by said element at a point on said surface offset laterally from a center line through the cone and element so that rotative movement of said cone provides a further adjustment of said element.
- 15 7. In an abrading tool having an abrading head, the combination of an abrading element 20 radially adjustable in said head, a pair of cones axially and rotatively movable in said head and having surfaces for engaging said element at points spaced along the body thereof, means for effecting axial movement of said cones in said head to adjust said element, said surfaces being so formed that rotative movement of said cones provides an endwise tilting adjustment of said element.
8. In an abrading tool having an abrading head, the combination of an abrading element 10 radially adjustable in said head, a pair of cones axially and rotatively movable in said head and having surfaces for engaging said element at points spaced along the body thereof, means for effecting axial movement of said cones in said head to adjust said element, said surfaces of said cones being respectively oppositely fluted so that a rotative movement of said cones provides an endwise tilting adjustment of said element. 15

THOMAS F. QUIGLEY.
